[57] CLAIM

The ornamental design for lamp or similar article, as shown and described.

DESCRIPTION

FIG. 1 is a perspective view of a lamp or similar article showing my new design as embodied in a floor lamp.

FIG. 2 is a top plan view thereof.

FIG. 3 is a front elevational view of the lamp or similar article of my design as embodied in a table lamp.

The front, rear and sides of each embodiment are identical.
